UNITED STATES PATENT OFFICE.

HENRY C. PRATT, OF CANANDAIGUA, NEW YORK.

CULTIVATOR.

SPECIFICATION forming part of Letters Patent No. 289,708, dated December 4, 1883.

Application filed August 15, 1883. (No model.)

To all whom it may concern:

Be it known that I, H. C. PRATT, a citizen of the United States of America, residing at Canandaigua, in the county of Ontario and 5 State of New York, have invented certain new and useful Improvements in Cultivators; and I do declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 Figure 1 of the drawings is a representation of a plan view of my improved cultivator. Fig. 2 is a side elevation of one-half of the cultivator. Fig. 3 is a front view of the axle. Fig. 4 is a detail view of the casting for the 20 section-rails. Fig. 5 is a detail of the connections of the sections to the axle. Figs. 6, 9, and 10 are details of the points and their castings. Figs. 7, 8, and 11 are detail views.

This invention has relation to a two-horse 25 riding corn and fallow cultivator combined; and it consists in the construction and novel arrangement of devices, as will be hereinafter fully described, and particularly pointed out in the claims appended hereto.

30 Referring by letter to the accompanying drawings, the axle *a* is made longer than is required for the corn-cultivator, in order that the wheels may be set farther apart, to admit of attaching another section between the corn- 35 cultivators when the implement is to be used as a fallow-cultivator. Holes *a'* through the axle, at suitable distances apart, permit the wheels and cultivators to be changed to such widths as will be suited to narrow or wide 40 rows; or the axle may be made with ends of malleable iron, having slots *b* running nearly the whole length of the spindles. These malleable-iron ends should be bolted to an arched center piece, as shown. The corn-cultivators 45 themselves may be also changed in breadth, to suit the distance between the rows, by loosening the three bolts *c*, *d*, and *e*, by which the rails of their frames are held together. The joints of the cultivator-frames are made to retain 50 the positions to which they may have been adjusted by the use of two castings, *f* and *f'*, having their meeting faces corrugated and

provided on their outer faces with seats *f''* for the frame-rails. The bolts *c d e*, passing through the frame-rails and the castings, hold 55 the parts firmly together, and the joint thus formed may be readily adjusted.

The cultivators are attached to castings *g*, that project from the axle forward. The castings *g* are made with a slot, *g'*, in their rear 60 ends, through which the bolt *g''*, that fastens them to the axle, passes. These slots are to provide means for easing or lowering the forward part of the cultivators, thereby regulating the depth of the cultivator-teeth. The 65 castings *g* are held in place by having their under faces corrugated to engage corrugations in a casting, *g''*, on the axle. This casting *g''* is curved in its under face to fit upon the axle, and has flanges on top to hold the projecting 70 arms *g* from moving laterally.

At the rear portions of the cultivator-frames guides *h* are used, to assist in regulating the depth of the cultivator-points. They are specially useful when it is desired to cultivate to a uniform depth and shallow. They 75 are made of steel and are bolted to castings *h'*, attached to the cultivator-frame. The castings *h'* are slotted to permit the guides to be adjusted vertically to change the depth to 80 which the cultivator-points run. The guides *h* are provided with wheels at the bottom, or cast-iron shoes may be used.

The cultivator-frames are raised and lowered by foot-levers *i i*, that are attached to 85 the cultivator-frames forward by castings *i' i'*, that rest on the frames and are bolted thereto. The castings *i' i'* are made with two vertical projections through which the levers *i i*, that constitute the foot-levers, pass, the holes in 90 said projections being made larger than the diameters of the rods, so that the levers may be turned sidewise enough to enter the notches *i''* at the bottoms of the guides *h*, that are used in connection with the levers when it is desired 95 to have the cultivator-frames remain suspended. The foot-levers are provided with foot-rests *i''*, on which the operator carries his feet. When it is desired to avoid cutting hills planted out of line with the row, the operator bears 100 down with his feet on the levers enough to raise the teeth out of the ground, and then passes sidewise or draws the cultivator toward him, as the case may require, by his feet.

Using the guides *k* in connection with the levers enables the operator to handle the cultivators more quickly and easily than though the cultivators had remained in the ground 5 when being moved to one side. Chains *l* are attached to the ends of the foot-levers *i* and pass over pulleys *l'* above in the cross-piece *l''*, secured to the rear end of the tongue. This cross-piece *l''* should be slotted vertically near 10 each end, so that the pulleys *l'* may be adjusted therein when the cultivators are to be moved on the axle. The chains are suitably fastened to the frames of the cultivators. The cross-piece *l''* is supported by braces running from 15 its ends to the axle, either upon the inside or the outside of the wheels.

To obtain a perfect draft-equalizer which shall be out of the way of the corn-row, I use two eveners, *m m'*, pivoted to the tongue and 20 connected by draft-rods *m''*. The evener *m* is composed of an iron bar bent angularly and extending downwardly at its ends. The ends are provided with a number of holes to adjust 25 the height of the draft. The cultivator-frames are attached to the arms *g* by passing the forward ends of their front rails through the slots in the forward ends of the arms *g*. Pins *n n'*, passed down through the rails in front and rear of the forward end of the arm *g*, form a 30 loose connection at the point of junction of the arms *g* and the frame-rails. Springs *n''* are interposed between the arm *g* and the rear pin, *n'*, to assist in throwing the cultivators back into position after having been shoved 35 aside.

One form of tooth which may be used in connection with the frames herein shown consists of a flat steel standard curved as shown, and secured to the under side of a casting, *o*, 40 within a flanged recess, *o'*, by two bolts. The casting *o* is composed of the parts *o'' o''*, having two sets of registering holes at the front and rear, passing laterally through them. The rear holes are for the bolt *o''*, and the front 45 holes for a wooden break-pin, *o''*. The part *o''* rests within the lower part, *o''*, and is provided with the corrugated plate *p*, which engages the ribbed plate *p'*, having a seat in its back for the rail of the cultivator-frame and 50 a bolt for attaching it. When the bolt *o''* and the break-pin *o''* are in the lower holes of the casting *o*, the tooth will incline a little forward. By putting the pin through the upper holes the tooth is given a good deal more pitch. It 55 may be made to incline backward by putting the bolt *o''* through the upper holes and the break-pin through the lower holes. When the tooth comes in contact with an obstruction, the wooden pin breaks and the tooth swings 60 back, thus preventing injury to the machine.

Although this construction is an excellent one, I prefer another, which I will now describe.

F designates a curved standard, which is twisted at the bottom to receive the point. 65 This tooth is secured to a casting, *G*, by a bolt, *G'*, which may occupy either of the three holes

made in the vertical portion of the casting, the adjustment of the tooth being made by changing this bolt in said holes. The forward end of the tooth bears against a wooden break-pin. The horizontal portion of the casting *G* is secured to the rail of the frame by the use of the castings *f* and *f'*, and a bolt, *e*, hereinbefore described, and is provided with two forward projections, *G''*, against which the break-pin bears. The bolt *G'*, which secures the standard to the casting *G*, is provided with a washer, *G''*, which has a square hole to receive the bolt, and the washer has also a projection to fit into one of the holes, either above 80 or below the standard, which prevents the washer from turning over, and consequently prevents the nuts from coming loose when the tooth vibrates. In sections of the country which are comparatively free from roots and 85 stones, this construction meets all the requirements; but when obstructions would be met with very frequently I employ a spring, *H*, which permits the tooth to yield without breaking the pin in the forward end of the curved 90 standard. This spring *H* is secured to the casting *G* by the bolt that secures the castings *f f'* to the rail, and is cut away at its forward end to straddle the standard *F*, and is formed with a sleeve on each arm of the bifurcation 95 to receive the ends of the break-pin. When the tooth meets an obstruction which gives sufficient resistance to overcome the power of the spring, it will yield, and the tooth will move back out of the ground. The lower ends of 100 the standards are provided with a hole for the bolt which secures the point to the standard. Three kinds of points are used. The point marked 1 is for cutting weeds and thistles. The point marked 2 is for digging and leveling 105 the ground, one edge being turned over to keep it in position. Point 3 is for throwing the earth to the corn-row.

x'' is a casting to be interposed between point 3 and the standard.

C and *D* also designate castings to be interposed between the points and the standards, to aid in securing the points to the standards firmly. Small narrow points may be secured directly to the standards. The casting *C* is for 115 the middle tooth of each cultivator, and *D* for the four outside teeth of each. It is preferred to have the outside standards attached by separate bolts to the frame, and the middle tooth or standard rather by the same bolt that 120 holds the frame.

The part *W* is to be placed between the corn-cultivators when the implement is to be used as a fallow-cultivator, and is raised and lowered with the corn-cultivators by the cross-bar 125 *M*, which hangs under the cultivators, and is connected to each by a short chain. The foot-levers are taken off of the corn-cultivators and put on the middle section, *W*, and are connected by the same chains and pulleys as before; but the ends of the lever-chains are fastened to the cross-bar *M* instead of to the cul-

tivators. By this arrangement all three of the sections are allowed to move up and down separately, to conform to uneven surfaces.

Having thus fully described my invention, 5 what I claim as new, and desire to secure by Letters Patent, is—

1. The axle *a*, provided with a slot or holes in its spindles, whereby the wheels may be changed thereon to vary the distance between 10 them, and are held in place by the plates *g*, substantially as specified.

2. The cultivator-frame consisting of the 15 four rails, arranged as shown, and having the standards for the cultivator-points secured thereto by the plates *f'f'* on the castings, for the standards and bolts passing through the rails, castings, and plates, substantially as specified.

3. The cultivator-frames secured to the 20 projecting arms *g* on each side of the wheels, said arms being secured to the axle by corrugated castings upon the axle, and bolts passed through arms, castings, and axle, whereby the frames may have lateral movement, substantially as specified.

4. The combination, with the frames secured 25 to the axle, as described, of the foot-levers *i*, having foot-rests, and fulcrumed at their forward ends in castings forward on the frames and between the wheels, so as to have lateral 30 movement in guides *K* on the frames, and the lever-chains connected to the ends of the said levers, passed over adjustable pulleys in slots

in a cross-piece, *l*, secured to the rear end of the tongue, and connected at their other ends 35 to the middles of the frames, substantially as specified.

5. The cultivator-frames connecting at the forward ends to the adjustable arms *g*, projecting forward from the axle, and provided near 40 the rear ends with the spring-steel guides *h*, which are vertically adjustable in bearings *h'*, for regulating the depth to which the points may run, substantially as specified.

6. The projecting arm *g*, slotted at the rear 45 and front ends, the rear end being corrugated in its under face, in combination with casting flanged and corrugated on its upper face to receive the rear end of the projecting arm and hold it from lateral motion, and a bolt for securing the arm and casting upon the axle, substantially as specified.

7. The combination of the standard *F*, with the casting *G*, having the vertical portion and the horizontal portion *G'*, the bolt *G'*, and 55 washer *G''*, the plates *f'f'*, the projections forming the bearing for the break-pin, and the bolt for securing the standard to the rail of the frame, substantially as specified.

In testimony whereof I affix my signature in 60 presence of witnesses.

HENRY C. PRATT.
